TALKING MACHINE

Honoré Fauchet, Paris, France

Application June 6, 1932, Serial No. 615,736
In France June 10, 1931

7 Claims. (Cl. 274—23)

In talking machines (phonographs) actually on the market, the tubular arm supporting the reproducer, as well as the solid arm supporting the pick-up, if electrical reproduction is under consideration, is rigid and is driven from the periphery of the record towards the center, or reversely, by the recording grooves, under the action of the rotation of the record, by describing an arc of circle throughout the recorded area.

For that purpose, this tubular or solid arm, according as an acoustic reproducer or a pick-up is under consideration, has its pivoting center placed outside the periphery of the record and at a point as far as possible away from the center of the latter, for reducing the driving stress to be overcome and also for reducing the pitch of the arc described by the reproducer on the recorded area.

This principle of construction of talking machines adopted by all manufacturers has numerous inconveniences among which the following can be cited: The sounds reproduced are lacking in faithfulness and clearness,—a reproduction in its entirety, orchestras in particular, considered on the totality of the recorded area, are lacking in homogeneity,—the recorded grooves wear off more rapidly on one and the same side, thus shortening the life of the record and causing it to rapidly lose its initial musical qualities,—the stylus of the reproducer wears off very quickly and always on one and the same side, thus rendering it practically useless for the audition of a second record,—usually, a scratching noise, which is at the least untimely, is prejudicial to the audition, and more particularly if soft music is being reproduced,—in practical use, if great care is not taken when placing the stylus in the first groove of the record already rotating, it sometimes happens that the reproducer is rapidly returned, by its pivoting arm, towards the center or towards the exterior of the record and scratches the latter, which, from that moment, can no longer be used for new auditions,—in practice, the audition of flexible records is impossible.

It has been proposed to devise talking machines and recording machines in which the arm supporting the reproducer or the recording oscillograph receives a rectilinear movement of translation.

In this apparatus, the tone arm is telescopic, it is rigidly connected to the tube supporting the reproducer, the connection of which with its supporting tube is effected by means of a uni-

versal joint having a flexible or resilient articulation.

The rectilinear movement of translation is imparted to the reproducer and, consequently, to the telescopic tube, by the motor of the apparatus, by means of a belt transmission or through gears actuating a worm meshing with a nut rigid with the supporting tube of the reproducer.

This general arrangement, in its application to phonographs, was chiefly adapted, owing to the rectilinear displacement of the reproducer, to avoid any useless friction on the sides of the grooves, to delay the wear of the record and needle or stylus of the reproducer, and, consequently, to partly remedy the inconvenience resulting, in these talking machines, from the angular movement described by the reproducer.

Now the recording pitches of records are very different according to the firms effecting the records and even for one and the same firm, and, for a recorded area from 85 to 90 m/m in width, a difference from 18 to 20 m/m is often noticed. In these conditions, it will be understood that the rectilinear displacement of the reproducer according to a radial line of the record, by means of a separate control as above set forth, cannot be successfully applied to reproducing phonographs which must be capable of utilizing all records found on the market.

In fact, after a short displacement of the reproducer moved according to a straight line by the above mentioned means, a wedging of the stylus on the sides of the groove, either in front, or behind, necessarily takes place, so that the result obtained is the reverse of that desired. The wear of the record and needle, as well as the scratching noise are increased; the resistant stress is rendered more variable on the totality of the recorded area and, consequently, the speed of rotation of the record varies, resulting in a lack of homogeneity in the reproduced sounds.

The telescopic tone arm supporting the reproducer receiving a rectilinear displacement from a separate driving device, has, moreover, the inconvenience of increasing by inertia, friction and wedging of the sliding parts, the driving stress to be overcome for ensuring the rotation of the record, which stress is very variable during the audition of one and the same record and still more from one record to another, if the differences of recording pitch between the various records used are taken into consideration. This results in a lack of homogeneity of

the reproduced sounds, and the necessity of employing a motor more powerful than that used in a standard phonograph found in the trade.

Finally, the method of connecting the reproducer and its supporting tube by a universal joint having a flexible articulation, seems to be particularly adopted in order to lessen, to a certain extent, the difference of the recording pitches noticed from one record to another.

- 10 Now, owing to this relative and very limited mobility of the reproducer relatively to its supporting arm, the groove brakes the movement of the reproducer, the needle or stylus rubs with greater force on one side of the groove than in 15 the case of pivotal movement, so that the scratching noise is increased and the wear of the record and needle is more rapid.

The present invention has for its object the provision of a tone arm, associated with a supporting means, particularly devised to remedy the foregoing objectionable features. The essential novel feature of the present invention is a tone arm including in its tubular wall an intermediate section consisting of a thin strip of resilient material spirally wound around the axis of the tone arm and connecting the end section thereof. The coils of this spiral section overlap so that the tone arm, as a whole, can be easily contracted or extended when slight force 30 is applied to that end.

During the operation of the phonograph, the stylus follows the record groove and tends to move inwardly the outer end of the tone arm. The spiral coils of the intermediate section 35 readily telescopic under the slight pressure imparted by the outer end of the tone arm and there is but slight friction between the stylus and the walls of the record groove. A yielding support is provided to maintain the several parts 40 of the tone arm in their axial relation during the movement of the outer end arm and the telescopic action of the intermediate section.

In order that the invention may be more clearly understood, a form of construction of 45 talking machine constructed according to the said invention, will be described hereinafter, by way of example only, with reference to the accompanying drawing, in which:

Fig. 1 is a longitudinal vertical section made 50 according to line A—A of Fig. 2.

Fig. 2 is a plan view.

Fig. 3 is a vertical cross section, on a smaller scale, made according to line B—B of Fig. 2.

Fig. 4 is a detail end view of the flared tubular bend forming an extension of the telescopic and extensible tone arm.

Fig. 5 is a section similar to Fig. 1, showing a modification on a smaller scale.

As illustrated in the accompanying drawing, 60 the box 1 of the phonograph according to the invention, which encloses, in the known manner, the spring or electric motor driving the turntable 2 on which the record is placed, is perforated, at the centre of its upper panel 3, with an opening for the passage of the vertical shaft 65 of the said turntable 2, and supports, on the said upper panel 3, the outer channel through which the sounds issue.

This outer channel comprises, according to 70 the present invention, a tone arm consisting of three tubular elements 4, 5 and 6.

The first element 4 is constituted by a rigid tube supporting the reproducer 7, the second element 5 by a tube constituted by a thin strip 75 of metal or other suitable material, wound in a

spiral in the same way as a conical spring which is secured, by its coil of greater diameter, in a socket 8 rigidly held in a collar 9 integral with the support 10 attached to the panel 3 of the box of the apparatus. There are fitted together in the socket 8: on one side, the outer coil of larger diameter of the resilient acoustic tube 5 and on the other side, the sleeve 28 terminating in the bend 6 which may be displaced in the said socket about the rod 12. The extreme edge 80 of the sleeve 28 is provided with notches 29, in one of which engages an abutment or finger 30 secured in the fixed socket 8 and maintaining the bend 6 in the position given to it.

This acoustic tube 5, which is light and astatic, is, owing to its constitution, resilient, telescopic and extensible, and in the coil of smaller diameter of this tube is secured the rigid tube 4 carrying the reproducer.

The third element of the outer channel through which the sounds issue, is constituted by a flared tubular bend 6 which fits, by its end of smaller diameter, in the socket 8 provided in the extension of the telescopic and extensible resilient tube 5, so that it can be 100 angularly moved about the longitudinal axis of the said tube 5, in order to modify, at will, the setting of the bend 6 and to move the opening of larger diameter of the latter, opposite the acoustic channel provided in the apparatus 105 and through which the sounds issue, as will be explained hereinafter.

The telescopic and extensible tube 5 is made in such a manner that its resiliency, limited to a very small value, naturally tends to hold the said tube in the nonextended position, its coils fitting in each other thus retracting the rigid tube 4 carrying the reproducer 7, towards the fixed socket 8 in which the telescopic and extensible tube is secured by its end opposite to that provided with the said rigid tube 4.

A slight pull exerted by hand on this rigid tube 4, which is suitably guided so that it can be moved in a straight line according to the longitudinal axis of the telescopic and extensible tube 5, overcomes the resistance of the conical spring constituting the said tube 5 and thus moves the latter to the extended position, in which the stylus 7a of the reproducer rests on a cushion 11 arranged in a housing of the upper panel 3 of the box of the apparatus, as clearly shown in Fig. 2.

In the form of construction in Figs. 1 to 4, the rigid tube 4 and reproducer 7 are rectilinearly guided by means of a metal rod 12 which is horizontally supported above the turntable 2 driving the record and is secured, at both ends, in two supports 13 and 14 secured on the upper panel 3 of the box of the apparatus; the tube 4 can freely slide between the supports 13 and 14, through the medium of a sleeve 15, secured in a socket 16 rigid with the said tube 4 and provided with linings 17, suitably lubricated and through which the fixed guide rod 12 passes.

In this example, this rod 12 is arranged in the 110 axis of the telescopic and extensible tube 5, it extends throughout the length of the latter, and, at the end opposite to the rigid tube 4, it passes through an opening of a socket 18 rigid with the flared tubular bend 6, so as to serve as supporting spindle on which the said tubular bend rotates.

In the modification illustrated in Fig. 5, the rigid tube 4 and the reproducer integral therewith are rectilinearly guided by means of a col- 115 120 125 130 135 140 145 150

lar 19 held on the tube 4 between two rings 20 of the said tube and sliding on two parallel rods 21 and 22, arranged outside the telescopic and extensible tube 5 and secured, the upper 5 one, in two supports 23 and 24, and the lower one, in one of these two supports and in another support indicated at 25.

In this form of construction, the collar 19 carries a sleeve 15a which, as that 15 described 10 above, slides on the upper rod 21 through the medium of lubricated linings 17a. The flared tubular bend 6, the end of smaller diameter of which is fitted in the fixed socket 8, is supported, by its socket 18, on a spindle 26, about 15 which it can be angularly moved and which is screwed in the support 23.

These two methods of guiding are given by way of example only and are adapted to allow the telescopic and extensible tube 5 to automatically collapse and to extend in the direction of its axis, by ensuring, at the same time, the rectilinear displacement of the rigid tube 4 carrying the reproducer 7. In both of the above forms of construction, the tube 5 encloses a 25 metal blade or rod 27 which is secured, at one of its ends, in the coil of smaller diameter of the tube 5 and is sufficiently rigid for preventing flexure of the said tube in the extended position.

The flared tubular bend 6, angularly movable 30 in the fixed socket 8, is guided in the latter by means of a sleeve 28 provided, on its extreme edge, with notches 29 which engage, according to the position given to the said bend, with an abutment 30 secured in the fixed socket 8 and 35 adapted to limit the angular displacements of this bend and to hold it stationary in definite positions.

In the positions shown in full lines in Figs. 1, 2, 4 and 5, the branch of larger cross section 40 of this tubular bend is vertically moved and its orifice opens opposite an acoustic channel through which the sounds issue and which is arranged within the box.

In the example illustrated, this channel is constituted by a tube 31, widely flared towards the orifice through which the sounds issue; this tube opens on the top of the box, or on one of the sides of the latter and is provided with a damper constituted by a fixed disc 32, in which openings 50 33 are cut out and under which is mounted, on a central shaft 34, a second disc 35 similar to the first one and provided with a knob 36 allowing to move it angularly, in order to totally or partially move in register both series of openings 55 and to thus modify the cross section of the orifice through which the sounds issue.

The various parts of the talking machine according to the invention occupying the position of rest shown in the drawing, the said machine 60 is set in action in the following manner:

Any record 41 is placed on the turntable 2 which is caused to rotate in the usual manner. The reproducer 7 is raised by causing the rigid tube carrying it to rock about its guide rod 12 65 and the stylus 7a of this reproducer is placed in the first groove of the record, which groove, in the example illustrated, is the external groove.

It will be understood from the foregoing that 70 the rigid tube 4 carrying the reproducer is simultaneously subjected to the combined action of the resilient returning force of the telescopic and extensible tube 5, of the groove of the record, and of the rotation of the latter, and that it is thereby directly and automatically

80 moved, on its guide rod, in a perfectly rectilinear direction, according to a radial line of the record, from the periphery towards the center of the latter, in the example under consideration, or reversely, by modifying the arrangement of the external acoustic channel through which the sounds issue.

Whatever may be the direction in which the reproducer is rectilinearly moved, the stylus of the latter, owing to the arrangement adopted, is always placed at the point of tangency of the groove in which it is engaged, whatever may be the point considered of its travel on the recorded area which can reach the center of the record. This stylus is thereby never wedged or abnormally pressed upon one of the sides of the groove; there is therefore no unnecessary and variable cause of friction capable of influencing the speed of rotation of the record and of creating an untimely scratching noise; in these conditions, the said stylus can very exactly follow the smallest sinuosities of the record and it allows to obtain a faithful reproduction.

The sounds reproduced are then pure, clearer, 100 more brilliant, and the homogeneity of the whole is better; the scratching noise is practically eliminated, the life of the record is lengthened as well as its musical qualities, the stylus or needle normally wears off and can, without in- 105 convenience, be used for the audition of several records.

When, as in the position shown in the drawing, the acoustic channel 31 is used, it is possible, by suitable displacement of the damper 35, to 110 reduce at will the volume of the sounds reproduced, in order to hear and discriminate in a better manner.

The arrangements described above are, of course, given by way of example only, and it is 115 obvious that the forms, materials and dimensions of the constituent parts can be modified without departing thereby from the scope of the invention. The same arrangements might also be applied to talking machines of any de- 120 signs for acoustic or electric audition and to all apparatus and machines for recording sounds and human voice, to the acoustic, electric and mechanic audition or reproduction of phonographic records.

In the example shown, the reproducer 7 is assumed to be a needle reproducer, so that the tube 4 is slightly flared for the easy travel of the sounds and is bent with rounded angles at both ends for its junction with the tube 3 and 130 with the reproducer 7.

This rigid acoustic tube 4, adapted to receive an acoustic reproducer, as illustrated in the drawing, might, in the case of electrical reproduction, be modified or even replaced by a rod 135 adapted to support a pick-up, but secured on the telescopic tube 5 and guided on the rod 12, as explained above.

I claim:

1. Talking machine comprising a reproducer, 140 a rigid arm supporting this reproducer, a telescopic and extensible resilient tone arm constituted by a thin band of metal wound in a spiral in the same way as a conical spring, a fixed support, a socket carried by this support 145 and in which is secured the outer coil of larger diameter of the said spring in the coil of smaller diameter of which is secured the rigid arm supporting the reproducer.

2. Talking machine comprising a reproducer, 150

a telescopic and extensible resilient tone arm, a rigid arm supporting the reproducer, a horizontal rod supporting the said rigid arm, arranged in the longitudinal axis of the tone arm 5 and passing through the latter throughout its length, a fixed bracket supporting each end of said rod, said rod rectilinearly guiding the reproducer according to a radial line of the record and ensuring the gradual telescoping of the said 10 tone arm.

3. Talking machine comprising a reproducer, a rigid arm supporting this reproducer, a telescopic and extensible resilient tone arm, a flared tubular bend through which the sounds issue, 15 and a horizontal guide rod supporting the said rigid arm and passing through the said tone arm and through the flared tubular bend.

4. Talking machine comprising a reproducer, a rigid arm supporting this reproducer, a telescopic and extensible resilient tone arm, two parallel rods arranged outside the said tone arm 20 for guiding the said reproducer, rings rigid with the arm supporting the reproducer, and a collar mounted between the said rings.

5. In a talking machine, a tone arm comprising a stationary end section, a movable end section, and an extensible-contractible intermediate section connecting the two end sections; said 25 intermediate section consisting of a spirally wound band of resilient material with the contiguous edges of the spirals overlapping to permit telescoping of the intermediate section during extension and contraction of the tone arm.

6. In a talking machine, a tone arm comprising a stationary end section, a movable end section, and an extensible-contractible intermediate section connecting the two end sections; said intermediate section consisting of a spirally wound band of resilient material with the contiguous edges of the spirals overlapping to permit telescoping of the intermediate section during extension and contraction of the tone arm; a fixed guide rod extending parallel to the longitudinal axis of the tone arm, and a guide mounted on the movable end section and slideable on the fixed rod to guide the movable end section during extension and contraction of the tone arm. 83

85
